UNITED STATES PATENT OFFICE

156,372

PHONOGRAPH CABINET

Walter A. Reed, New Orleans, La.

Application March 24, 1947, Serial No. 137,844

Term of patent 14 years

(Cl. D56—4)

To all whom it may concern:

Be it known that I, Walter A. Reed, a citizen of the United States, residing at New Orleans, in the county of Orleans and State of Louisiana, have invented a new, original, and ornamental Design for a Phonograph Cabinet, of which the following is a specification, reference being had to the accompanying drawing, forming part thereof, in which the single figure of the drawing is a front perspective view of a phonograph cabinet showing my design, the rear portion being substantially the same except for the omission of the pair of louver panels shown in the upper part of the cabinet.

I claim:

The ornamental design for a phonograph cabinet, substantially as shown and described.

WALTER A. REED.
